UNITED STATES PATENT OFFICE

90,427

DESIGN FOR A SET OF PLAYING CARDS

Thomas C. Steidle, Fairmont, W. Va.

Application February 27, 1933. Serial No. 47,332

Term of patent 14 years

To all whom it may concern:

Be it known that I, THOMAS C. STEIDLEY, a citizen of the United States, residing at Fairmont, in the county of Marion, State of West Virginia, have invented a new, original, and ornamental Design for a Set of Playing Cards, of which the following is a specification, reference being had to the accompanying drawing, forming a part thereof.

Figs. 1 through 8 of the drawings are front views of certain cards of the set, and Fig. 9 is a back view of all cards of the set.

The set of playing cards contains 104 cards and comprises four series of 26 cards each, each series having different symbols thereon as shown in Figs. 1 to 4 inclusive, the characters of two series preferably being printed in different color from the other two series.

I claim:

The ornamental design for a set of playing cards as shown and described.

THOMAS C. STEIDLEY.
